ELIMINATING ELECTRIC SHOCK

Filed Dec. 19, 1927

UNITED STATES PATENT OFFICE

JOHN H. HUNT, OF DETROIT, MICHIGAN, ASSIGNOR TO GENERAL MOTORS RESEARCH CORPORATION, OF DETROIT, MICHIGAN, A CORPORATION OF DELAWARE

ELIMINATING ELECTRIC SHOCK

Application filed December 19, 1927. Serial No. 241,241.

The present invention relates to the dissipation of static charges which tend at times to accumulate on a person walking or sitting on a covering material formed with a thick soft fabric.

Operators and users of automobiles, especially of closed cars, which are provided with upholstery covered with a thick plush fabric are often troubled with discharges of static electricity. These discharges are especially prevalent in cold dry weather when woolen clothing is worn. The sliding contact of the woolen clothing with the thick fabric covering the upholstery produces a considerable charge of static which is discharged when the operator moves his hand close to the door handle or other metallic part of the car. The sparks and shocks accompanying these static discharges are often great enough to cause considerable annoyance to a nervous, sensitive person.

Similar occurrences are encountered in hotels and dwelling houses where thick rugs, carpets and chair coverings are provided. The sliding friction accompanying the movement of a person across the room or into the seat often creates such a considerable charge that when the person moves his hand close to an electrically grounded metallic object and the discharge occurs, the accompanying spark and sound are distinct enough to be nerve racking and the accompanying shock may be quite severe.

It is an object of the present invention to avoid the inconvenience occasioned by such static discharges by preventing their accumulation. I accomplish this by providing means in the fabric for dissipating the static charges so that they will not accumulate on the persons in contact therewith. In the case of an automobile, I provide means in the seat covering and for the floor mat for dissipating the charges.

Other objects and advantages of the invention will appear in the course of the following description, taken in connection with the accompanying drawing and appended claim.

In the drawing:
50 Figure 1 is a perspective view, partly bro-

ken away, of a portion of automobile including the driver's seat and adjacent parts.

Figure 2 is a vertical longitudinal section through the front portion of the cushion and including the adjacent part of the floor mat. 55

Figure 3 is an enlarged longitudinal section through a portion of the fabric covering the front seat, showing diagrammatically the weave of the cloth and wire.

Figure 4 is a diagrammatic view showing 60 a modified form of the weaving of the wire with the fabric.

Figure 5 is a sectional view showing the weaving of the wire with a fabric of general form. 65

Referring to the drawing, I have illustrated a portion of an automobile with a closed body, the door and body on the right hand side being omitted for purposes of illustration. The seat is of the usual form and comprises a metallic base frame 36 and a metallic back rest frame 10. The back rest is upholstered as at 12, and supported on the base 36 is an upholstered cushion 14. The floor of the car is covered with a mat 16. 70 Woven in the cloth fabric covering the cushion 14 and back rest 12 are a number of fine wires, the position of which is indicated by the lines 18. The wires 8 extend longitudinally of the car in the fabric covering the 80 seat and in the floor mat and are laterally spaced at regular intervals. 75

As shown in Figure 1, the metallic frame 10 of the back rest is bent forward on its upper edge, as at 11. The edge of the cloth covering the upholstered portion 12 of the seat is extended down against the flange 11 and is held thereagainst by a metal lath 13, extending the width of the seat and held against the flange 11 by means of spaced bolts 85 (not shown). The remainder of the back rest is of usual construction, comprising coil springs 15 covered with burlap 17, the outer fabric being held spaced from the burlap 17 by means of the upholstery 19. The structure described insures that the wires 18 in the fabric covering the upholstered portion 12 of the back rest will be electrically grounded on the metallic frame 10 and hence on the 90 frame of the car. 95

In Figure 2 I have illustrated the ground-
ing connection of the wires in the cushion
14. Extending along the lower front edge
of the cushion is a wooden frame piece 20 on
3 the upper side of which is fastened the wire
screen or mesh 22 which supports the coil
springs which are surrounded by the usual
tubular sacks 24. Fixed to the frame piece
20 and extending over the springs is the bur-
10 lap cover 26. Arranged over the cover 26
is the upholstery 28 and covering this is the
woven fabric 30.

The lower edge of the fabric 30 is turned
15 under the frame piece 20 and is fixed thereto
by means of a metallic lath 33 extending
along the under side of frame piece 20 and
fixed thereto by means of screws 32. The
heads of the screws 32 rest on the flange 34 of
20 the sheet metal frame 36 upon which the seat
is supported. The frame 36 rests on the floor
of the car but contacts at the ends with the
arm 38 of the metallic strip 40 which is sup-
25 ported on the longitudinal frame member 42
of the car. The lower part of the fabric 30 is
firmly pressed between frame piece 20 and
metal lath 33, this arrangement insuring that
the wires 18 in the cushion will be grounded
with the frame of the car.

Extending across the floor of the car is a
30 metallic strip 46 which is integral with the
metallic strip 40. The wires 18 in the floor
mat are grounded by contact with the strip 46.

The weave of the fabric is illustrated dia-
grammatically in Figure 3. This view illus-
35 trates a cloth of double weave in which the
numeral 50 indicates the woof and 52 the
warp. The strands 54 are woven in to give
the cloth a velvety effect. The numeral 18
40 indicates the strand of wire woven into the
fabric. This wire may be of any metal from
which can be formed a fine tough wire.

In Figure 4 is illustrated a looser weave
in which lines 58 indicate the woof, lines 60
the warp and lines 61 the strands woven in
45 to give the velvety effect. The wire 62 is
woven in more loosely than in the fabric illus-
trated in Figure 3.

In Figure 5 I have illustrated a strip 64
50 which may be of any material which is used
to cover the seat or floor of the car, whether
woven or not. Sewed or woven into this
fabric are the wires 66 which form a network
therein. Adjacent parallel wires may be
55 spaced any desired distance apart.

By the structure described, any static
charge which occurs as a result of the rubbing
of the clothing of the occupant against the
fabric covering the front seat will be carried
60 away by the network of wires and the accu-
mulation of a considerable charge on the per-
son of the occupant will be avoided. It may
be considered sufficient to have the wires
woven into the floor mat alone since there
65 is usually sufficient moisture about the shoes
of the occupant to establish electrical contact

between the person of the occupant and the
wires in the floor mat.

The metal which is placed in the fabric to
70 prevent the accumulation of static charges
may be arranged in a wide variety of ways
which will at once suggest themselves to one
familiar with the art. It may be considered
sufficient to arrange the conducting metal in
75 the seat fabric alone or in the mat alone.
The wires may be arranged in a single direc-
tion or they may be woven in with both the
warp and the woof. It is sufficient that it
be placed in the car adjacent the seat in such
80 a relation that it will be in close enough con-
tact with the apparel of the occupant to dis-
sipate static charges as they occur. The
metal in the fabric may be grounded in a wide
variety of ways, since there are a large num-
85 ber of metallic parts adjacent the seat which
are electrically connected with the frame of
the car.

In any case where the static dissipating me-
tallic wire is placed in a floor covering, a
90 grounding element must be placed in the
floor in such a position as to contact with the
metal in the fabric.

I claim:

Upholstering material for an automotive
95 vehicle comprising a fabric covering in which
are carried spaced metallic conductors elec-
trically grounded with the frame of the ve-
hicle for preventing the accumulation of
static charges on the person of the occupant
of the vehicle.

In testimony whereof I affix my signature. 100
JOHN H. HUNT.
